UNITED STATES PATENT OFFICE.

BAPTIST DREHER, OF CLEVELAND, OHIO.

STRINGING PIANO-FORTES.

SPECIFICATION forming part of Letters Patent No. 228,738, dated June 15, 1880.

Application filed September 2, 1879.

To all whom it may concern:

Be it known that I, BAPTIST DREHER, of Cleveland, in the county of Cuyahoga and State of Ohio, have invented certain new and useful Improvements in Method of Stringing Pianos; and I do hereby declare the following to be a full, clear, and exact description of the invention, such as will enable others skilled in the art to which it pertains to make and use it, reference being had to the accompanying drawings, which form part of this specification.

In the drawings, Figure 1 is a side view, illustrating my invention. Fig. 2 is a plan view of the same. Fig. 3 is a plan view, showing a modification of my invention; and Fig. 4 is a plan view, illustrating another modification thereof. Fig. 5 is a plan view, representing the device as applied to a three-stringed piano.

A represents the sounding-board; B B', the bridges or agraffes; B², the agraffe-bar or bridge; C, the hitch-pins; D, the hitch-pin block; E, the wrest-plank, and F the tuning or wrest pins. G G are loops or agraffes, through which the wires or strings pass just before being wound upon the wrest-pins F. H represents the equalizing-bar. K K' are the strings or wires.

It will be noticed that I place the upper surface of the hitch-pin block D and the bearing-surfaces of the agraffes B B' G and the surface of the wrest-plank E substantially on a line or common plane, so that with the equalizing-bar H removed the strings, if drawn taut, would have no material or operative bearing between hitch-pin and wrest-pin. The equalizing-bar H is located between the agraffes B B' and the hitch-pins C. It is made of any suitable shape or material, and it should be thick enough in cross-section so that when woven, as it were, through the wires, in the manner indicated in the drawings, such wires K as pass over it shall exert an upward pull upon their agraffes, and such wires K' as pass under this equalizing-bar will push or press downward upon their respective agraffes. Thus, if the wires of every other note in the scale are strung over the equalizing-bar and the rest of the wires under said bar, as shown in Fig. 2 of the drawings, there will be no ma-

terial pressure whatever upon the sounding-board A beneath the agraffe-bar B².

Instead of arranging the strings of every alternate note as just above specified, every alternate string may be passed respectively above or below the equalizing-bar H, as shown in Fig. 3 of the drawings; or, as shown at Fig. 4, all the strings of two, three, or more successive notes may be arranged, say, over the equalizing-bar and all the strings of an equal number of next succeeding notes be passed beneath.

My invention is equally applicable to the "square," the "upright," or the "grand" type of pianos.

I am aware that an equalizing-bar has been employed in connection with terraced hitch-pin blocks so arranged and constructed that a part of the strings shall be attached above and a part below the level or plane of the agraffes on the sounding-board bridge. In a construction of this type the neutralization of pressure upon the sounding-board is primarily and principally dependent upon the up-and-down pull of the strings on account of the terraced hitch-pin block, as aforesaid, to which they are attached, and not to the equalizing-bar, which in such a construction is employed as a supplemental or auxiliary addition, and not as an essential, so far as relieving the sounding-board from pressure is concerned.

My invention differs from such a construction mainly in the feature of making the equalizing-bar H the sole and only element whereby an equalization of the up-and-down pull of the strings upon the sounding-board is effected; and this I accomplish by arranging the various parts to which the strings are attached or over or through which they pass substantially on a level or a common plane, and then, when the equalizing-bar H is applied, as specified, it alone becomes the element through which the sounding-board is relieved from pressure and permitted a more free and unobstructed vibration.

What I claim is—

1. The described method of stringing pianos, which consists in stretching the wires between two points that are in the same plane with the agraffes or passages B upon the sounding-board bridge through which said wires are

passed, and in arranging some of said wires over and the rest under an equalizing-bar, H, located in relation to said agraffes or passages B substantially as shown, whereby an equalization of the up and the down pull of said wires upon the sounding-board bridge is effected and pressure upon the sounding-board due to the tension of the wires relieved.

2. In a piano, the combination, with agraffes B B' and hitch-pins C, of strings K K', secured to said agraffes and hitch-pins in the

same longitudinal plane, and equalizing-bar H, interwoven transversely among the strings between said agraffes and pins, substantially as set forth.

In testimony whereof I have signed my name to this specification in the presence of two subscribing witnesses.

BAPTIST DREHER.
